COMBINED PICNIC TABLE AND MULTIPLE BENCH UNIT

James E. Miller, Birmingham, Mich.
(12900 W. Ten Mile Road, South Lyon, Mich. 48178)

Filed July 5, 1974, Ser. No. 485,849

Term of patent 14 years

Int. Cl. D6—05

U.S. Cl. D6—45

FIG. 1

FIG. 3

FIG. 2

FIG. 4

FIG. 5

FIG. 6

FIG. 1 is a top plan view of a combined picnic table and multiple bench unit showing my design.

FIG. 2 is a front elevational view thereof, the rear elevational view being a mirror image thereof.

FIG. 3 is an end elevational view thereof, the opposite end view being identical.

FIG. 4 is a cross-sectional view taken on line 4—4 of FIG. 2.

FIG. 5 is a front perspective view of the design.

FIG. 6 is an opposite side and front perspective view of the design.

I claim:

The ornamental design for a combined picnic table and multiple bench unit, as shown and described.
